UNITED STATES PATENT OFFICE.

FRANK P. MILLS, OF CHICAGO, ILLINOIS.

HOISTING APPARATUS.

SPECIFICATION forming part of Letters Patent No. 376,672, dated January 17, 1888.

Application filed June 18, 1887. Serial No. 241,711. (No model.)

To all whom it may concern:

Be it known that I, FRANK P. MILLS, a citizen of the United States, residing at Chicago, in the county of Cook and State of Illinois, 5 have invented certain new and useful Improvements in Hoisting Apparatus, of which I do declare the following to be a full, clear, and exact description, reference being had to the accompanying drawings, forming part of this 10 specification.

My present invention, while applicable in whole or in part to a variety of other uses, is particularly designed for unloading from the holds of vessels cargoes of ore, coal, and such 15 like material commonly removed in tubs, which tubs, after being swung over the dock, are dumped to discharge their contents.

My invention consists in the various novel features of construction, hereinafter described, 20 illustrated in the accompanying drawings, and particularly defined in the claims at the end of this specification.

Figure 1 is a front view of the hoisting apparatus embodying my invention. Fig. 2 is a 25 view, partly in central vertical section and partly in side elevation, of the mechanism shown in Fig. 1. Fig. 3 is a detail view in cross-section through the swivel-bracket at the top of the mast, the section being taken just 30 above the pulley. Fig. 4 is an enlarged view in horizontal section through the mast, above the traveling carriage of the dumping-arm, the dumping-arm, the jib, and the mechanism for adjusting the jib being shown in plan. 35 Fig. 5 is an enlarged detail view, in front elevation, (parts being shown in vertical section,) of the lower portion of the mast and jib and traveling carriage. Fig. 6 is an enlarged detail view from the rear side of the upper portion 40 of the mast and the swivel-bracket attached thereto, the pivoted top bearing of the mast being shown in section. Fig. 7 is an enlarged detail view, partly in section and partly 45 in side elevation, of the clutch device and the bearing-plates adjacent thereto. Fig. 8 is a detail view in vertical cross-section on line xx of Fig. 7. Fig. 9 is a detail plan view of the clutch.

In the accompanying drawings my invention is shown as applied to a form of hoisting apparatus particularly designed for unloading 50 cargoes of ore and coal from the holds of ves-

sels, and while I have shown the mechanism for hoisting but a single tub at each lift, it will be readily understood that in practice a 55 number of similar devices may be arranged side by side at distances apart approximating the distances between the hatchways of ordinary vessels.

A designates a suitable frame-work erected 60 at any desired height above the level of the dock, and by preference provided with the rails A', whereon will travel the cars which serve to receive the ore or coal from the delivery-chute B and deposit the same at any desired 65 points upon the dock. The delivery-chute D, which is of the usual or suitable construction, is sustained upon the frame-work A², a portion of which frame-work comprises the vertical beams A³ and A⁴, which rise 70 slightly above the top of the mast C.

Between the vertical beams A³ and A⁴ extend the upper and lower cross-beams, A⁵ and A⁶, within which are pivotally sustained the upper and lower ends of the mast C. The pivotal bearing of the upper end of the mast C consists, preferably, of the tubes D and D', the tube D being passed through a suitable opening in the cross-beam A⁵, while the tube D' fits within a similar opening formed in the 80 cross-head c of the mast C, and the inner ends of these tubes D and D' are planed off to form a smooth bearing, and their flanges d and d' are bolted, respectively, to the inner faces of the cross-beam A⁵ and the cross-head c of the 85 mast. Through the tubes D and D' passes the pivot-bolt E, the headed end of which bears upon a plate or washer, e, its threaded end being provided with a suitable nut, e'; and from this construction it will be seen that the pivot-bolt E serves to connect the cross-head c of the mast to the cross-beam A⁵ in such manner that the mast can swivel with respect to such beam. The mast C comprises the side bars, c' and c'', which rest upon the base-bar C' at their lower 90 ends, and at their upper ends are united by the cross-head c, and the pivotal bearing for the lower end of the mast is effected by means of the tubes F and F', the tube F entering a suitable hole formed through the base-bar C', 100 while the tube F' enters a similar hole formed in the cross-bar A⁶ below the bottom of the mast. The tubes F and F' are provided, respectively, with the flanges f and f', which

will be bolted to the respective bars C' and A⁶, and from the face of the flange f' rises the annular bearing plate or rib f², within which projects the lower end of the tube F, and 5 against the upper edge of which bears the lower face of the flange f. From this construction it will be seen that when the tubes F and F' have been properly set within the base-bar C' and cross-beam A⁶, to which they are respectively attached, and the lower end of the tube F has been placed within the annular rib or plate f², the upper edge of this annular rib will afford a seat or bearing upon which the lower face of the flange f can be turned, and 15 this annular rib will also guard against any danger of the lateral displacement of the lower end of the mast.

The outer ends of the base-bar C' will be provided with the journal-blocks G, from 20 which project the journals g, that serve to pivotally sustain the inner ends of the side bars H and H' of the jib, the inner ends of these bars being provided with suitable bearing-blocks adapted to receive the journals g. The 25 side bars H and H' of the jib converge at their outer ends, which are connected together, as seen in Fig. 4, and at the outer ends of these bars is journaled the pulley I, sustained in a suitable bearing-bracket, i, and having 30 its periphery grooved to receive the hoisting-rope J, which is trained over the pulley.

Upon the under side of the outer end of the jib is suitably bolted the detent device K, the side arms, k, of which are preferably cast in 35 piece with the top rib or plate, k', and the bottom plate, k², and are formed at such distance apart as to permit the hoisting-rope J to move freely between the arms k and yet arrest the stop J' after the hoisting-rope has received an 40 initial lift. These arms k of the detent extend some distance in front of the pulley I, and thus serve to prevent the contact of the stop J' with the pulley I, and consequently bear the strain 45 of the hoisting-rope when the stop J' is arrested by the arms. These arms k are curved, in order to permit the stop or ball J' to ride over the outer face thereof as the jib is lifted into the open socket or "back check," k³, preferably formed in piece with the bottom plate, 50 k², at the base of the arms k. The under side of this open socket or back check, k³, is slotted, so as to permit the ball to ride freely into the socket, as shown by dotted lines, Fig. 2, and when it is in this position it is obvious 55 that the hoisting-rope will extend between the arms k and the sides of the socket k³.

My purpose in providing a back check or socket for the stop J' is to insure the outward movement of the empty tub as the hoisting-rope is released for the purpose of lowering the tub, and it is obvious that so long as the stop J' is within the socket the tub will be 60 swung outward as the jib is lowered, and hence will be returned to the proper position for re-loading.

From the foregoing construction it will be seen that the side bars H and H', of which the

jib is constructed, are connected at their inner ends to the base-bar C' in such manner that the jib is free to swing in vertical direction, 70 and as the base-bar C' is capable of being turned with a corresponding movement of the mast it is apparent, also, that the jib and mast will turn in unison about the swivel-bearings of the mast. My purpose in thus making provision 75 for the lateral movement of the mast and jib is to permit the outer end of the jib being brought more directly over the hatchways of the vessel to be unloaded; and in order to permit the mast and jib to be fixed when brought 80 to the proper position above the hatchway I have provided the segment-tracks L, which are fixed to the cross-beam A⁶ near the outer ends of and beneath the base-bar C'; and these segment tracks L will, by preference, be formed 85 with grooves l, adapted to receive the headed ends of the adjusting-bolts L', which pass through the ends of the base-bar C' and are provided with the set-nuts l', which serve to firmly hold the base-bar C' at any desired point 90 upon the segment-tracks. To the upper end of the mast C will be bolted the buffer-frame M, which projects, as seen in Fig. 2, some slight distance from the face of the mast, and serves to arrest the vertically-swinging movement of the jib, and the extent of the downward movement of the jib will be limited by a stay-rope, h², one end of which is shown as connected to the top of the mast, while the opposite end is attached to a coiled spring, h¹, 100 fastened to the outer end of the jib. This stay-rope h² will be of suitable length, so that by the adjustment of the rope the extent of the downward movement of the jib can be varied 105 as desired.

Near the top of the mast C, and between the side bars c' and c², are fixed the journal-brackets N, in which will be journaled the grooved pulley N', over which the hoisting-rope J will pass as it comes from the pulley I, mounted on the outer end of the jib, and from the pulley N' this hoisting-rope will pass over other pulleys to a suitable winding-drum, as will be presently described.

From the construction of parts as thus far defined it will be seen that when power is applied to the hoisting-rope this rope will be drawn over the pulleys N' and I, thereby lifting the tub or load until the stop or ball J', that is fixed at a suitable point upon the hoisting-rope, strikes the outer edges of the arms k of the detent device K, and the movement of the hoisting-rope over the pulley I being thus arrested, the further winding of this rope will cause the jib to swing in vertical direction until its upper end strikes against the buffer-frame M at the top of the mast. By this means an initial vertical lift will be given to the loaded tub, which, as the hoisting-rope is further wound, will be swung over the point 130 at which the load is to be discharged. As the jib is thus swung upward, the stop or ball J' on the hoisting-rope will ride against the face of the arms k of the detent K until the stop

enters the back check or socket, k^3 , as shown by dotted lines in Fig. 2; and it is obvious that when the hoisting-rope is released, after the load of the tub has been dumped, the stop J' will be retained within the back check or socket, k^3 , until the jib has swung downward a sufficient extent to prevent the tub from lowering into the chute B, after which the stop J' will pass from out the socket. It is also apparent that by thus temporarily retaining the stop J' within the back check the initial downward movement of the jib is insured.

In order to effect the automatic dumping or discharge of the contents of the loaded tubs, I have provided the mechanism to be next described. To the side bars c' and c^2 of the mast are fixed the rails c^3 and c^4 , upon which will move the wheels o of the traveling carriage O, this traveling carriage consisting of a cast-metal open frame, in the ends of which the axles of the wheel o are journaled, and about the center of which are formed suitable bearings for the axle of the pulley O', over which the winding-rope will pass.

To the traveling carriage O, near its top, are bolted the inner ends of the side bars p and p' of what I term, for convenience, the "dumping-arm" P, these side bars being braced by standards p^2 , that extend from the bars to a suitable bearing near the lower portion of the carriage O. The main portions of the side bars p and p' are parallel and at a slight distance apart; but their outer ends are expanded or bent laterally, forming guide-arms to insure the delivery of the hoisting-rope into engagement with a suitable clutch or other retaining device as this rope is swung inward by the raising of the jib.

In order to properly retain the rope and prevent its backward movement after it has thus been caught by the side bars of the dumping-arm, I have placed upon the dumping-arm the clutch device R, (more particularly illustrated in Figs. 7, 8, and 9 of the drawings,) the shank r of this clutch being journaled within the rear portion of the bearing-plates R' and R^2 , which are bolted together and are held in position between the side bars p and p' of the dumping-arm.

The bearing-plate R' is provided upon its upper surface with the flanges r' , that rest upon and are bolted to the upper faces of the side arms p and p' , and the lower bearing-plate, R^2 , is bolted to the under side of the upper bearing-plate, R' , as shown in Fig. 7. Each of the bearing-plates R' and R^2 is bifurcated, and the inner faces of their forked ends are joined together to form the journal-bearing for the shank r of the clutch, while the outer portions of their forked ends are inclined, so as to properly direct the hoisting-rope into the jaw of the clutch, as will be presently explained.

The clutch R is provided at the rear end of its shank with the weighted arm R^3 , and at its opposite or front end is formed with the hook-arm or jaw R^4 and the upwardly-extending re-

leasing-arm R^5 , and these arms R^4 and R^5 are held between the bifurcated ends of the bearing-plates R' and R^2 , the sides of these plates being cut away, as shown in Fig. 8, to permit the free movement of the arms of the clutch, as will be presently seen. The upper face of the bearing-plate R' is provided with the inclined recess r^2 , into which the upper end of the releasing-arm R^5 will slightly project, for a purpose to be presently explained. At the base of the releasing-arm R^5 of the clutch is formed the inclined surface r^3 , against which will bear the sleeve J^2 , that is carried upon the hoisting-rope in a manner free to slide thereon.

The purpose of the inclined surface r^3 at the base of the releasing-arm R^5 is to cause the hook-arm R^4 of the clutch to be swung in such manner that its bent end will pass in front of the trip-sleeve J^2 of the hoisting-rope when the jib has been raised to a sufficient extent to bring the trip-sleeve against the inclined surface r^3 , and thus prevent the backward movement of the trip-sleeve and the hoisting-rope away from the dumping-arm. This checking of the backward movement of the hoisting-rope is important, since, if no such provision were made, the rope would sway back and forth, and consequently would prevent the load being dumped with certainty into the proper receptacle. The weighted arm R^3 is so disposed with respect to the arms R^4 and R^5 of the clutch that it will temporarily retain the hook-arm either in position for holding the hoisting-rope or in position to permit the hoisting-rope to swing outward, according as this weighted arm is shifted to one side or the other of the vertical central line, as will be presently explained.

The extent of the swinging movement of the clutch in one direction will be limited by means of the stop r^5 , formed at the base of the releasing-arm R^5 and engaging with a shoulder, r^6 , formed on the plate R^2 , while the swinging movement of the clutch in opposite direction will be limited by the contact of the hook-arm R^4 with the inner face of the shoulder r^6 . The purpose of the releasing-arm R^5 of the clutch is to throw the hook-arm R^4 at the proper time out of action, so that when the jib is lowered the hoisting-rope can swing away from the dumping-arm; and this backward swinging of the hook-arm R^4 is effected when the dumping-arm P is raised a sufficient distance to cause the shoulder j of the trip sleeve J^2 to depress the upper end of the releasing-arm R^5 , as will be presently explained.

It is obvious that it will be advantageous to check the swinging movement of the hoisting-rope when the jib is raised, whether a dumping-arm is to be used or not; and it is equally obvious that other forms of retaining device will serve the purpose of the clutch. I therefore wish my invention to be understood as embracing broadly within its scope the employment of arms for directing the hoisting-rope into a suitable retaining device; and

while the term "clutch" is employed for convenience of description, I do not wish the claims to be understood as restricted to this particular form of retaining device.

To the lower end of the carriage O is fixed a cup-shaped plate, S, and upon the top of the base-bar C', and between the side bars c' and c'' of the mast, is placed a block, s, upon the top of which is fastened a cup-shaped plate, S', and between the cup-shaped plates S and S' is held the coiled spring S², the purpose of which will presently appear. To an eye or staple, o', formed at the bottom of the carriage O, is connected one end of the rope T, which rope passes through suitable holes formed in the plates S and S', and through the intermediate spring, S², and also through a hole formed in the block s, and through the tubes F and F' around a grooved pulley, T', that is journaled in a suitable bracket affixed to the under side of the cross-beam A⁶, and thence over a grooved pulley, T², journaled to the vertical beam A⁴, and is attached at its lower end to the counter-balance T³. The purpose of the counter-balance T³ is to prevent the traveling-carriage O from being lifted during the initial movement of the hoisting-rope and until the outer end of the jib has been swung upward into contact with the buffer-frame M at the top of the mast, a further purpose of this counter-balance being to restore the carriage O to its lowest position when the load has been discharged from the tub and the hoisting-rope is released. The spring S² serves to break the shock of the downward movement of the carriage, and to prevent injury thereby to the base-bar C' of the mast. At the top of the mast, and within suitable brackets, V and V', are journaled the ends of the swivel-frame W, within which is mounted the grooved pulley W', over which is trained the hoisting-rope that passes thence to suitable mechanism for winding the same. The swivel-frame W is formed of the side bars w and end bars, w', from which the journals of this frame project, and the lower journal, w², of this swivel-frame is perforated to permit the hoisting-rope J to pass freely through this journal and over the pulley W'. It will thus be seen that the hoisting-rope J passes first over the pulley W', thence downward over the pulley O' of the traveling carriage, thence upward over the pulley N' at the top of the mast, thence over the pulley I at the outer end of the jib, and thence between the arms k of the detent device to the bail of the tub, to which it will be attached by any suitable form of hook or catch.

From the foregoing description the operation of my improved apparatus will be seen to be as follows: Assuming the parts to be in the relative position shown by the full lines in Fig. 2, if now the hoisting-rope be wound for the purpose of lifting the loaded tub from the vessel, it is obvious that the weight of the traveling carriage O, aided by the counter-balance T³, will prevent the vertical move-

ment of this carriage until the loaded tub has received its initial vertical lift and until the stop or ball J' has come into engagement with the detent device K at the outer end of the jib, and until the jib has been swung upward by the further winding of the hoisting-rope to such extent that the outer end of the jib is brought into contact with the buffer-frame M at the top of the mast. When the parts have assumed this position, it will be found that the tripping-sleeve J², which is free to move upon the hoisting-rope, and adjacent the tub, will have been guided, by the expanded ends of the arms p and p' into engagement with the clutch R, between the forks of the plates R' R², and will bear upon the inclined surface r³ at the base of the releasing-arm R⁵ of the clutch with such force as to overcome the force of the weighted arm R³ and cause the bent or hooked end of the hook-arm R⁴ to swing in front of the sleeve J², and thus prevent its outward movement, and so check any further tendency of the hoisting-rope and tub to swing. The weighted arm R³ will retain the hook-arm R⁴ in this position until the releasing-arm R⁵ is depressed, as will presently appear. As the hoisting-rope continues to be wound, the weight of the traveling carriage O and of the counter-balance T³ will be overcome, and the dumping-arm will be moved in vertical direction to the position shown by the dotted lines in Fig. 2. As the dumping-arm is thus moved upward, the flanged portion or shoulder j of the sleeve J² will enter the recess r² in the upper part of the bearing-plate R', which recess is smaller at its bottom than the shoulder j, and in doing so will bear upon and depress the end of the releasing-arm R⁵, causing this arm to swing downward, and forcing the weighted arm R³ to the other side of its center of oscillation and causing the hook-arm R⁴ to be swung away from in front of the tripping-sleeve J², and it is obvious that the weighted arm R³ will temporarily retain the clutch in this position. The further upward movement of the dumping-arm will cause the lifting of the tripping-sleeve J², which is free to slide upon the hoisting-rope, and as this sleeve is connected by the chain J³ with the bottom of the tub it will cause the tub to be upset and its contents to be dumped into the chute B. If, now, the hoisting-rope be unwound, it is obvious that the weight of the carriage O and of the counter-balance T³ will restore the carriage and the dumping-arm to their lowest position, after which the jib will swing downward and the tub will be lowered to the desired position. It is obvious that the back check k, at the base of the detent K on the end of the jib, will cause the tub to swing outward as the jib is lowered, and the hoisting-rope will pass freely over the clutch and the guide-arms during this outward swing.

It is obvious that if the distance between the hatchways of the vessels to be unloaded is greater than the distance between the masts of the adjacent hoisting devices the jibs of either or both masts can be moved laterally,

and, by means of the segment-tracks L and adjusting-bolts L', can be set at such position as to bring the tubs above the hatchways. My purpose in mounting in a swivel-bracket the 5 pulley W', over which the hoisting-rope passes from near the top of the mast to the hoisting-engine, is to permit the position of this pulley to remain constant irrespective of any shifting of the mast and the jib made 10 necessary for the purpose of bringing the outer end of the jib above the hatchway of the vessel.

It will be readily understood that the details of construction above set out may be considerably varied by the skilled mechanic without departing from the spirit of my invention, and that certain features of the invention may be used independently of the others.

Having thus described my invention, what I 20 claim as new, and desire to secure by Letters Patent, is—

1. In a hoisting apparatus, the combination, with a suitable sustaining-frame and with a mast pivoted at the top and bottom, of a base- 25 bar to which said mast is connected, and a jib comprising side bars pivotally connected at their inner ends to the ends of said base-bar, said base-bar serving to sustain both the mast and the jib, and being adjustably connected 30 with the frame-work, whereby the position of the mast and jib with respect to said frame-work may be simultaneously adjusted, substantially as described.

2. In a hoisting apparatus, the combination, 35 with a suitable sustaining-frame, of a mast pivotally mounted therein, a jib comprising side bars, a base-bar to which said side bars of the jib, are pivoted, and segment-plates and adjusting-bolts for determining the position of 40 the mast and jib, substantially as described.

3. In a hoisting apparatus, the combination, 45 with the jib pivoted to swing in vertical direction and a hoisting-rope passing over said jib, of a clutch adapted to lock the hoisting-rope against direct outward movement when the jib is raised, substantially as described.

4. In a hoisting apparatus, the combination, 50 with a jib pivoted to swing in vertical direction and a hoisting-rope passing over said jib, of a clutch for retaining the hoisting-rope as the jib is raised, and expanded guide-arms for directing said rope into the clutch, substantially as described.

5. In a hoisting apparatus, the combination, 55 with a mast and a jib pivoted at its inner end, of a vertically-movable dumping-arm, and a hoisting-rope connected with the jib and with the dumping-arm, substantially as described.

6. In a hoisting apparatus, the combination, 60 with a mast and with a jib pivoted to swing

in vertical direction, of a vertically-movable dumping-arm, a hoisting-rope, and a movable sleeve on said dumping-arm, with which the dumping-arm will engage, substantially as described.

65

7. In a hoisting apparatus, the combination, with the mast, of a jib pivoted at its inner end and provided at its outer end with a detent device, a vertically-movable dumping-arm, and a hoisting-rope provided with a stop to engage with the detent on the outer end of the jib, and with a movable trip-sleeve to engage with the dumping-arm, substantially as described.

8. In a hoisting apparatus, the combination, 75 with the mast provided with pulleys at its upper end and with a jib, of a vertically-movable frame or carriage provided with a pulley, a dumping-arm carried by said frame or carriage, and a hoisting-rope provided with a 80 trip-sleeve adapted to be moved by the dumping-arm, substantially as described.

9. In a hoisting apparatus, the combination, 85 with the mast provided with pulleys at its upper end, of a vertically-swinging jib provided at its outer end with a pulley and with a detent device, a vertically-movable frame or carriage sustained by said mast and provided with a pulley, a dumping-arm connected with said frame or carriage, and a hoisting-rope 90 passing oversaid several pulleys and provided with a stop to engage with the detent and the jib, and with a movable trip-sleeve to engage with the dumping-arm, substantially as described.

95

10. In a hoisting apparatus, the combination, with the mast and the jib, of a vertically-movable dumping-arm having jaws to admit the hoisting-rope, and a suitable clutch device for retaining the rope within said jaws, substantially as described.

11. In a hoisting apparatus, the combination, 100 with the crane and the jib, of a vertically-movable dumping-arm and a hoisting-rope provided with the vertically-movable trip-sleeve, 105 and a chain leading from said trip-sleeve for connection with the base of the tub, substantially as described.

12. In a hoisting apparatus, the combination, 110 with the mast and the jib and the hoisting-rope, of a vertically-movable dumping-arm, a movable carriage for sustaining said dumping-arm, and a weight connected with said carriage for restoring the same to the lowest position, substantially as described.
